UNITED STATES PATENT OFFICE.

MAHLON CHARLES MYERS, OF BRANTFORD, ONTARIO, CANADA, ASSIGNOR TO BENJAMIN THOMAS LEGGETT, EDUARD HERBERT NEWMAN, THE YOUNGER, AND WILLIAM E. MINO, ALL OF BRANTFORD, CANADA, TRUSTEES FOR THE MYERS PERFECT SPRING SPOKE WHEEL SYNDICATE.

SPRING-WHEEL.

1,162,706.

Specification of Letters Patent. Patented Nov. 30, 1915.

Application filed November 20, 1911. Serial No. 661,445.

To all whom it may concern:

Be it known that I, MAHLON CHARLES MYERS, of Brantford, in the Province of Ontario, Dominion of Canada, a subject of the King of Great Britain, have invented certain new and useful Improvements in Spring-Wheels, of which the following is a specification.

This invention relates to improvements in spring wheels, and the general objects of the invention are to simplify and improve the construction of spring spokes, to cause them to possess a uniform resiliency, to resist lateral twisting and to be readily attached 15 to the rim of the wheel.

More particular objects of the invention are to provide an improved form of connecting means on the outer end of the spoke by which it may be connected to the rim of the 20 wheel, such means being adapted to resist lateral twisting, to be readily attached and detached and to securely hold spokes in proper alined position. This object is accomplished by forming the connecting member integral with the spoke, of a practically 25 non-flexible character and formed with means to interlock with the rim as pointed out hereinafter.

A further object of the invention is to 30 prevent lateral twisting of the inner portion of the spoke and to give an increased support to said inner portion without unduly increasing the weight or impairing the resiliency. This object is accomplished by 35 providing one or more integral cross stays between the forks formed on the inner end of the spoke.

A still further object is to prevent the 40 flexible portion of the spoke, during use, contacting or bearing against the rim of the wheel, and to effect this, the connecting member or outer end of the spoke is so formed that it will support the flexible portion of the wheel a distance inwardly from 45 the rim and at the same time support it with the end tangential to the rim, whereby a maximum amount of resiliency will be offered and the end of the flexible portion will be free to bend inwardly and outwardly in 50 a radial direction.

These and other features of the invention are all more fully set forth and described in

the accompanying specification and drawings.

In the drawings: Figure 1 is a perspective view of a wheel constructed in accordance with my invention. Fig. 2 is a vertical section on the line 2-2, Fig. 1. Fig. 3 is an elevation partially in section of the wheel. Fig. 4 is a perspective view of one 60 of the spokes.

In the drawings like characters of reference indicate corresponding parts in all the figures.

Referring to the drawings, *a* represents 65 the hub, of any suitable character, and connected to the rim *b* also of any desirable construction by a set of spring spokes, each of which is constructed in a novel manner herein described. Each spoke is formed of 70 a thin flat strip of metal, the greater portion of which is of a resilient character. The extreme outer end, however, of each spoke is substantially non-flexible and is adapted to prevent the flexible portion, when 75 it bends, from contacting with the rim. This non-flexible portion is also so shaped that it will support the extreme end 10 of the flexible portion in a direction substantially parallel to a tangent to the rim, 80 whereby the flexible portion of the spoke will be bent more or less to the shape of a semicircle, permitting the outer end to yield freely in a radial direction.

The outer substantially non-flexible portion is formed into an integral connecting member 11 which has means to engage the rim, the portion engaged with the rim being turned tangentially with respect thereto, and to provide for this tangential turn and 90 also for the support of the end of the flexible portion in the manner previously described, the connecting member is of substantially double ogee or canted curved shape and the particular form illustrated is 95 formed with a curve *e* at the outer end of resilient or flexible portion *f* of the spoke. While the connecting member may be attached to the rim in any of the usual ordinary ways, by bolts, rivets, keys or the like, 100 I prefer to employ the improved form of novel construction which I have devised and which comprises an interlocking end on the connecting member adapted to project

through the slot *i* in the rim. A plurality of these spokes may be provided if desired. As illustrated, the end of the connecting member is formed with a right angle turn *g*, the extreme end of which is formed with a lip *h* adapted to extend concentrically with the rim and to bear against the inner face thereof, the connecting member being formed on the outer side with a shoulder *b'* to engage and contact with the rim, said seat or shoulder being substantially tangential to the inner surface of the rim.

To prevent twisting of the connecting member and any lateral movement of the spoke as a whole, means are provided on the inner portion of it to engage with the rim, the particular form of such means illustrated comprising a pin *l* adapted to enter 20 a corresponding recess *j* in the inner surface of the rim.

The inner end of each spoke is formed with diverging forks *f'* and *f''* and to prevent twisting of these forks with respect 25 to each other and to obviate the tendency to lateral movement, they are connected by a plurality of transversely extending stays 14. It will be noted that the forks converge to the point 10 at which they join the connecting member, and that the sides of the connecting member from this juncture converge less rapidly toward each other. The forks may be connected to the hub in a variety 30 of ways and for the sake of illustration I have shown a dovetail tongue *h'* on the inner extremities of the forks *f'* and *f''*, said tongues being adapted to seat within sockets *g'* and *g''* in the hub. The forks *f'* and *f''* diverge evenly from the solid piece *f* 35 toward the inner end of the spoke so that when the wheel parts are assembled, the medium lines of the hub, spoke and rim will be in alinement. By means of this construction I am able to obtain the full resilience 40 of the spokes for the deflections of the wheel and resist the lateral strains upon it which would cause it to buckle as a result of the load on the hub or the impact of a relatively immovable object against the rim.

50 As many changes could be made in the above construction and many apparently

widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. In a spring wheel, a rim and spring 60 spokes, each spoke being formed with a continuous bow-shaped curve from the hub to near the rim and having an integral connecting member of double ogee shape adapted to support the extremity of the curved 65 portion inwardly from the rim, the end of the connecting member being formed with a right angled turn having its lip adapted to engage on the outer face, and extend concentrically with the rim.

2. In a spring wheel, a rim and spring 70 spokes, each spoke being formed with a continuous bow-shaped curve from the hub to near the rim and having an integral connecting member of double ogee shape provided with a shoulder on its outer side designed to engage and contact substantially tangentially with the inner surface of the rim.

3. In a spring wheel, a rim and spring 80 spokes, each spoke having on its inner end evenly diverging forks provided with dovetailed tongues on the ends thereof and transversely extending stays connecting the forks, the said spokes being formed in a 85 continuous bow-shaped curve from the hub to near the rim and having an integral connecting member of double ogee shape adapted to support the extremity of the curved portion inwardly from the rim, the end of 90 the connecting member being formed with a right angled turn adapted to engage on the outer face and extend concentrically with the rim, and a pin formed integral with the connecting member adapted to engage the 95 rim, substantially as described.

In witness whereof I have hereunto set my hand in the presence of two witnesses.

MAHLON CHARLES MYERS.
